DESIGN FOR A PHONOGRAPH CABINET OR SIMILAR ARTICLE

Leland S. Briggs, Douglaston, N. Y., assignor to Dictaphone Corporation, New York, N. Y., a corporation of New York

Application May 17, 1934, Serial No. 51,825

Term of patent 14 years

To all whom it may concern:

Be it known that I, LELAND S. BRIGGS, a citizen of the United States, and resident at Virginia Road, Douglaston, county of Queens, and State of New York, have invented a new, original, and ornamental Design for a Phonograph Cabinet or Similar Article, of which the following is a specification, reference being had to the accompanying drawing, forming part thereof.

The figure is a perspective view of a phonograph cabinet, showing my new design.

I claim:

The ornamental design for a phonograph cabinet or similar article, as shown.

In testimony whereof, I have signed my name to this specification this 16th day of May, 1934.

LELAND S. BRIGGS.
